UNITED STATES PATENT OFFICE.

CHARLES KADE, OF CHICAGO, ILLINOIS, ASSIGNOR OF ONE-HALF TO
WILLIAM KREICKER, OF SAME PLACE.

LEAF-SUPPORT FOR TABLES.

SPECIFICATION forming part of Letters Patent No. 339,427, dated April 6, 1886.

Application filed December 22, 1885. Serial No. 186,418. (No model.)

To all whom it may concern:

Be it known that I, CHARLES KADE, a citizen of the United States of America, residing at Chicago, in the county of Cook and State 5 of Illinois, have invented certain new and useful Improvements in Leaf-Supports for Tables, &c., of which the following is a specification, reference being had therein to the accompanying drawings.

This invention has for its object to produce a table-leaf support that is simple, strong, and durable, and that can be readily manipulated.

The first part of my invention consists of a 15 table-leaf support composed of two bars pivotally secured one to the table-frame and the other to the table-leaf, each such bar having to its free end a loop through which the other bar is passed, both such loops forming guides 20 for holding the bars on a relative parallel position during extension and contraction of the support; such loops also serving to form shoulders to each other to prevent the entire disconnection of the bars or the extension of such 25 leaf-support beyond the desired limit.

The second part of my invention consists in a leaf-spring secured against one of the bars and engaging the notched end of the other bar when such supporting-brace is extended 30 to its limit, for holding and preventing from swinging the table-leaf in either direction, all as more fully described, and specifically claimed.

In the accompanying drawings, Figure 1 35 represents the end elevation of the device holding the table-leaf on its elevated position; Fig. 2, a similar view of the device, with the table-leaf released and folded against the end of the table, and Fig. 3 a section on line $\alpha\alpha$ in Fig. 1.

Corresponding letters in the several figures 40 of the drawings designate like parts.

A denotes a flat bar, pivoted by a suitable hinge-bracket, a , to the frame of the table, and B is another similar bar pivoted by a suitable 45 hinge-bracket, b , to the table-leaf. The bar A has secured to its extremity a loop, c , through which the bar B is passed, and the bar B has secured to its extremity a loop, d , through which the bar A is passed in a manner 50 that the loop of each bar forms a rigid

guide for the other bar, which loops, interlocking, will prevent such bars A and B from disengagement, and will form stops or shoulders to each other, limiting the extension of such bars to the desired length. A leaf-spring, 55 C, is secured by riveting against bar B, the vibratable end of which spring C engages with a notch, e , filed into the end of bar A, when such bars A and B are extended to their limit, and will lock them on their extended position. 60

With raising the table-leaf to a horizontal position, so as to form a continuation of the table proper, the bars A and B will be extended by sliding by each other until the loops c and d will butt against each other, and will 65 allow no farther movement, when the spring C will jump into the notch e of bar A, and will thus lock the support, forming a rigid brace for such table-leaf, as shown in Fig. 1.

For folding the table-leaf again, to hang to 70 the end of the table, the spring C only needs depressing with the finger, when it will occupy a position between the bars A and B, which now can slide past each other until they occupy a position side by side, as shown in Fig. 2. 75

A great advantage of this table-leaf support is that it cannot be extended beyond the desired length required for forming a brace for holding the table-leaf on a horizontal position, and therefore the hinges by which such table-leaf is connected to the table proper cannot 8c be strained or broken.

What I claim is—

1. The combination, with a table and a hinged leaf thereof, of an arm secured to the 85 table-frame and provided at one end with a loop, a second arm pivoted to the leaf and provided with a loop, the arms arranged to slide each in the loop of the other, and a suitable locking device for such parts, as set forth. 90

2. A table-leaf support consisting of bars A and B, each provided with a loop, c and d , forming guides for such bars, and of a suitable locking device for holding such bars in their extended position, substantially as described, 95 to operate as specified.

3. A table-leaf support consisting of bars A and B, each provided with a loop, c and d , forming guides for such bars, and of leaf-spring C, secured to bar B, and engaging with a notch 100

or shoulder of bar A, all substantially as described, to operate as specified.

4. A table-leaf support consisting of bar A, pivotally secured to the table-frame, and provided with a loop, *c*, and notch or shoulder *e*, and of bar B, pivotally secured to the table-leaf and provided with loop *d*, and leaf-spring C, the whole being constructed and arranged

substantially as described, to operate as specified.

In testimony whereof I affix my signature in presence of two witnesses.

CHARLES KADE.
